UNITED STATES PATENT OFFICE.

ONO B. EMERSON, OF WATERVILLE, MINNESOTA, ASSIGNOR OF ONE-HALF TO FRANK W. GREENE, OF WATERVILLE, MINNESOTA.

CAR-SEAL.

No. 834,197.

Specification of Letters Patent.

Patented Oct. 23, 1906.

Application filed October 12, 1905. Serial No. 282,361.

To all whom it may concern:

Be it known that I, ONO B. EMERSON, a citizen of the United States, residing at Waterville, in the county of Lesueur and State of Minnesota, have invented certain new and useful Improvements in Car-Seals; and I do hereby declare the following to be a full, clear, and exact description of the invention, such as will enable others skilled in the art to which it appertains to make and use the same.

My invention has for its object to provide a simple and extremely efficient car-seal of very small cost; and to this end it consists of the novel devices and combinations of devices hereinafter described, and defined in the claims.

For the sake of definiteness the improved device is herein designated as a "car-seal;" but it will of course be understood that it is not limited to such use, but is capable of general application wherever a seal of the character will be found serviceable. This improved seal is constructed from a single piece of tin or other thin sheet metal, which is first stamped out in the form of a blank and is then bent to its proper form.

The improved seal is illustrated in the accompanying drawings, wherein like characters indicate like parts throughout the several views.

Referring to the drawings, Figure 1 is a view in front elevation, showing the complete seal with its ends interlocked. Fig. 2 is a view, partly in side elevation and partly in section, on the line $x^2 x^3$ of Fig. 1. Fig. 3 is an enlarged section taken on the line $x^2 x^3$ of Fig. 1. Fig. 4 is a plan view showing the metal blank as it appears after having been stamped out, and Fig. 5 is a section on the line $x^5 x^5$ of Fig. 4.

Referring first to the blank as shown in Figs. 4 and 5, the numeral 1 indicates the long ribbon-like body of the seal, the same having at one end an integrally-formed head 2 3 and having at its other end a relatively small head 4. The head 4 has laterally-spaced side lips 4^a and an intermediate lip 4^b . The lips 4^a and 4^b are reversely bent at angles with respect to the body 1, as shown by dotted lines in Fig. 5 and by full lines in Figs. 2 and 3. The head 2 3 is made up of two parts that are adapted to be folded together to form the lock-pocket of the com-

pleted seal. The parts 2 and 3 have intersecting circular edges, and when folded together the marginal portions 2^a of the part 2 are adapted to be folded over the segmental edges of the part 3. The folded edges 2^a should be tightly rolled or clamped on the edges of the part 3, and they may be further secured by soldering or brazing or riveting, if found desirable. The part 3 is depressed or laterally offset at 5 to form a pocket or seat for the head 4, and it is provided with a wide lip 6, that projects at the outer extremity of the depression 5 and is bent in the completed device into the form indicated by dotted lines in Fig. 5 and by full lines in Figs. 2 and 3.

At the junction of the body-strip 1 with the portion 2 the blank is stamped out to form a relatively narrow lip 7, which when the device is completed is bent into the form shown by dotted lines in Fig. 5 and in Figs. 2 and 3 by full lines. When the lip 6 is bent in the form described, the curved portion 8 is formed, and when the lip 7 is bent in the form described the curved portion 9 is formed. The curved portions 8 and 9 by reason of the method of stamping, cutting, and bending the same herein described possess resiliency and the character of springs. When the blank is bent and pressed together to form the completed seal, the curved portions 8 and 9 come in contact and effectually close the door or opening into the head or pocket of the seal and must be forced apart when the head 4 is being placed in operative position, of which forcing apart their spring character renders them capable. The lips 6 and 7 are stamped and cut from the same piece of metal from which the seal is made. The lip 6 is bent inwardly and downwardly, thus forming a spring below and beyond the curved portion 8. The lip 7 is bent inwardly and upwardly, thus forming a spring above and beyond the curved portion 9. These lips may be cut in various forms and turned and folded in various ways, as the remaining elements of the interlocking mechanism may be varied. The lip 7, being in the space in the pocket above the curved portions 8 and 9, yields only when the head 4 is inserted through and between the curved portions 8 and 9 and on account of its resiliency and spring character is the essential and governing element in the interlocking mechanism, while the resiliency and spring character of

the lip 6 insure that that element will always be ready to engage with the other elements in locking the seal. When the device is completed, the two lips 6 and 7 extend into the 5 pocket from the mouth thereof and are pressed together under their own spring tension, so that they constitute a pair of opposing but coöperating spring lock prongs or lips.

- 10. The spring lip or prong 7 is of such width that it is adapted to pass through the perforation formed by the bending out of the lip 4^b of the head 4. Hence when the head 4 is forced into the pocket 5 between the curved 15 portions 8 and 9 and between the spring lock lips or prongs 6 7 said lips 6 and 7 will be separated to permit the lips 4^a 4^b to pass; but when the head 4 is pulled downward the spring-lip 7 will catch under the lip 4^b and 20 will be caused to pass through the perforation of the head 4, while the wide spring-lip 6 will catch under the two lips 4^a, thereby securely locking the head 4 against removal from the said pocket. By reason of their 25 spring character the curved portions 8 and 9 assist in securing the head 4 against removal from the pocket.

This device, while extremely simple and of very small cost, has been found extremely 30 efficient for the purposes had in view. It is perfectly reliable in its action, and when the ends of the sealing-strip are once interlocked they can be separated only by destroying the seal. As is evident, the interlocking lips of 35 the seal are protected by the inclosing walls of the pocket 5 in such manner that they cannot be disengaged without cutting into the pocket, and thus destroying the seal. The entrance to the pocket 5 is normally and en- 40 tirely closed by the curved portions 8 and 9, which yield sufficiently to permit the entrance of the head 4 when it is desired to lock the seal. It is evident that the head which contains the pocket 5, as well as other parts 45 of the seal, may take different forms without departing from the spirit of my invention.

What I claim, and desire to secure by Letters Patent of the United States, is as follows:

- 1. A seal constructed of a single piece of 50 metal having at one end a duplex head bent transversely upon itself to form a pocket, one portion of said head being dished to provide the pocket-cavity, springs formed integrally with said piece of material and disposed 55 within said pocket, said piece of material having at its other end reversely-bent lips

adapted to enter said pocket and interlock with the said interior springs.

2. A seal constructed from a single piece of thin metal, and comprising a body-strip 1, 60 the head 4 at one end thereof, the head 2 3 at the other end thereof, the part 2 having the inwardly-bent spring-lip 7 and the part 3 having the inwardly-bent wide lip 6 and pocket 5, said parts 2 and 3 being folded together and having their edges clenched, and said head 4 having the reversely-bent lips 4^a 4^b, and which head 4 is insertible into the pocket 5, between the spring-lips 6 and 7, and which lips 6 and 7 interlock with said 65 lips 4^a and 4^b, substantially as described.

3. A seal constructed of a single piece of metal comprising a pocket at one end, spring-lips arranged within said pocket, and at the mouth of said pocket spring resilient portions 75 normally in contact to close the entrance to the pocket.

4. A seal constructed of a single piece of metal, comprising a pocket, and having at the mouth of the pocket resilient portions 80 normally in contact and closing entrance into the pocket, and internally-arranged springs constituting continuations of said resilient portions and adapted to coöperate with other members to lock the seal. 85

5. A seal constructed from a single piece of thin metal and comprising a body-strip 1, the head 4 at one end thereof, the head 2, 3, at the other end thereof, the part 2 having the inwardly-bent spring-lip 7, provided with a 90 curved portion 9, said lip cut from the same piece of metal, and the part 3 having the inwardly-bent spring-lip 6 and pocket 5, said spring-lip 6 being provided with the curved portion 8 and cut from the same piece of 95 metal, said parts 2, 3, being folded together and having their edges clenched, and when so folded and clenched the said folded edges 8, 9, coming in contact and normally closing the opening to the pocket 5, and said head 4 having reversely-bent lips 4^a, 4^b, and which head 4 is insertible into the pocket 5 between the curved portions 8 and 9, and between the spring-lips 6 and 7, which spring-lips 6 and 7 interlock with the lips 4^a, 4^b. 100

In testimony whereof I affix my signature in presence of two witnesses.

ONO B. EMERSON.
